UNITED STATES PATENT OFFICE.

VICTOR E. TOLLEFSON, OF ELK POINT, SOUTH DAKOTA, ASSIGNOR, BY MESNE ASSIGNMENTS, TO INTERNATIONAL AUTOMOBILE SUPPLY CO., A CORPORATION OF ILLINOIS.

AUTOMOBILE-HORN.

1,084,675.

Specification of Letters Patent. Patented Jan. 20, 1914.

Application filed June 5, 1912, Serial No. 701,862. Renewed December 6, 1913. Serial No. 805,161.

To all whom it may concern:

Be it known that I, VICTOR E. TOLLEFSON, a citizen of the United States, residing at Elk Point, in the county of Union and State 5 of South Dakota, have invented new and useful Improvements in Automobile-Horns, of which the following is a full, clear, and exact description.

My invention relates to horns, and particularly horns for automobiles, launches, and the like, designed to be operated by the exhaust from the engines thereof.

The object of my invention is to provide a series of pleasant sounding resonant tubes 15 adapted to be sounded simultaneously to produce a harmonious combination of sounds, for the signaling and warning purposes for which the instrument is intended.

A further object of my invention is to accomplish the foregoing results by a simple and economical construction of parts that will be held firmly together and withstand the jars and vibrations to which the instrument, particularly when used as an automobile 25 horn, will be subjected. This I accomplish by the means hereinafter fully described, and as particularly pointed out in the claims.

In the drawings, Figure 1 is a side view 30 of my invention. Fig. 2 is a transverse section thereof taken on dotted line 2—2, Fig. 1. Fig. 3 is a transverse section taken on dotted line 3, 3, Fig. 1. Fig. 4 is a longitudinal central section of the lower part of 35 the instrument and adjacent portions of the horn connected thereto.

My invention is adapted to be secured to the exhaust pipe of the engine of an automobile or other vehicle by means of a coupling A. This coupling is tubular in construction, and about its center of length its bore is divided by a transverse partition a, which is, preferably, somewhat dome-shaped, and below this partition its bore is screw-threaded and above the bore is inclined outward.

I prefer to use four resonant tubes B. This being the case, I provide the dome-shaped partition with four equi-distant 50 openings, whose radii from the axis of the coupling is the same, and I insert and secure the lower circular ends of four tubular nozzles b, b, in these openings, and arrange them so that their upper flattened ends incline outward to the upper end edge of

said coupling. This edge is provided with recesses c, c, next the upper ends of said nozzles, substantially as shown. Near the upper end of the coupling it is provided with a circumferential platform C, and this platform has its outer edge provided with a circumferential flange d, that projects from the periphery thereof toward the tubes, and terminates in the same transverse plane as the upper edge of the coupling. Opposite, 60 and in the same radii as the upper ends of nozzles b, b, and recesses c, c, this flange d is cut-away or provided with recesses e, that are, preferably, larger than the recesses c, substantially as shown in the drawings. 65

The lower open ends of the four resonant tubes are cut off obliquely, and are inserted down into and secured in the sockets of a metallic holder or cage, substantially as 70 shown. This holder consists of a base portion F, from which four equi-distant sockets f, f, arise, the inner circumferences of which correspond to the outer circumferences of the tubes, and when the tubes are inserted from above the downward movement thereof is limited by their lower ends coming in contact with the inclined or countersunk surface g at the lower ends of the sockets. 75 Near the outer surfaces the sockets are provided with transversely elongated mouths G, and the front of each socket, and also the rear portions thereof nearest the center around which said tubes are arranged, are cut-away above the plane of the mouth so as to lighten the weight of the holder, and so as to render the merging walls of the 80 sockets somewhat elastic. 85

The reduced lower end of each socket is 90 provided with a reduced opening h through which the discharge from the nozzles b, located below and in line therewith, discharges. The rearmost portion of each of these openings is closed by a segmental web j, the object of which is to deflect the current 95 of the discharge from the nozzle forward as it enters the tube. 100

Now, where the tubes are assembled in the holder, the oblique edges of the lower ends thereof are made to face outward, and the highest segments of the said lower edges terminate in about the same plane as the uppermost portions of the mouths G of the sockets. When in this position and the exhaust gases of the automobile engine are 110

discharged through the coupling and nozzles *b* into the tubes *B* the latter emit a sufficiently loud and harmonious combination of sounds to perfectly fulfil the requirements of this class of instruments, without shrieking. The surplus volume of exhaust gas escapes out through recesses *c* and *e* and the hissing of the tubes as they yield up their harmonious voices is thus avoided.

10 In order to retain the tubes firmly in their assembled positions, I surround them at a point near the upper ends of the sockets of the holder with an inclosing frame *H*, which latter is, preferably, made of cast metal, 15 and I provide this frame with a series of four equi-distant lugs *k*, *k*, that depend downward and lap over and down past the upper edges of the holder midway between adjoining sockets. Screws *m*, *m*, extend 20 through these lugs *k*, *k*, through the metal connecting adjoining sockets between the tubes, and their inner ends are tapped into a central boss *K*. It is obvious that if these screws are tightened, the webbing 25 composing the sockets, conterminous with the longitudinal slots or cut-away portions thereof, will clamp the tubes correspondingly tighter.

I also provide a frame *J* for retaining the tubes in their assembled position, which is located at a point farther away from said sockets than frame *H*. This frame *J* consists of a cast metal member, the webbing of which entirely surrounds each tube and is 35 solid and unbroken between the same. This frame is held in place by a bit of solder, or in any other suitable manner. Of course both frames, *H* and *J*, may be dispensed with, if desired. I much prefer their use, 40 however, or their equivalents.

What I claim as new is:—

1. A horn having a coupling, a holder having a base connected to the coupling, said base having apertures therein, said coupling 45 having lateral openings corresponding to the openings in the base, sockets on said base, tubes having closed outer ends and open inner ends, the said open ends of the tubes being seated in the sockets, and means for 50 conducting exhaust gases from the coupling through the openings of the base.

2. A horn having a coupling, a holder having a base connected to the coupling, said base having apertures therein, said coupling 55 having lateral openings corresponding to the openings in the base, sockets on said base, tubes having closed outer ends and open inner ends, the said inner ends being beveled, the said open ends of the tubes 60 being seated in the sockets, means for conducting exhaust gases from the coupling through the openings of the base.

3. A horn comprising a coupling, a series 65 of resonant tubes having one end closed and their opposite ends cut obliquely, and a

holder secured to one end of said coupling and having a series of sockets therein the ends of which adjacent said coupling are tapered and provided with contracted extremities, the open ends of said tubes being inserted into the said sockets.

4. A horn comprising a coupling, a holder having a series of sockets secured to one end thereof, a series of tubes having one end closed and having their open ends inserted and retained in said sockets, and a series of nozzles inclosed within said coupling and discharging into said tubes; the end edge of said coupling next the ends of said nozzles being recessed.

5. A horn comprising a tubular coupling having a transverse partition, a series of nozzles one end of each of which is secured in and penetrates through said partition, a holder having a series of sockets therein which is secured to the end of said coupling adjacent the discharge ends of said nozzles, and a series of resonant tubes, each having one end closed and their open ends inserted and secured in said sockets, the said open ends being beveled forming with the socket openings, ports for the escape of the gases.

6. A horn comprising a tubular coupling having a transverse partition, a series of nozzles one end of each of which is secured in and penetrates through said partition, a holder having a series of sockets therein which is secured to the end of said coupling adjacent the discharge ends of said nozzles, and a series of resonant tubes each having one end closed and their open ends inserted and secured in said sockets, said tubes having beveled inner ends; the said holder adjacent the discharge ends of said nozzles being recessed and forming with the beveled ends of the tubes discharge openings for the gases.

7. A horn comprising a coupling, a holder having a series of longitudinally elongated sockets arranged around a common center, a series of tubes each having one end closed and having their open ends inserted and retained in said sockets, and means for clamping said tubes comprising a central boss and screws tapped radially through the ends of said sockets opposite said coupling into said boss.

8. A horn comprising a coupling, a holder having a series of sockets therein, a series of tubes each having one end closed and having their open ends inserted and retained in said sockets and adapted to receive a gaseous discharge from said coupling, and means comprising a central boss surrounded by the tubes, lugs between the tubes and practically embracing the said tubes, means for securing the lugs to the boss independent of said holder for clamping said tubes together.

9. A horn comprising a series of resonant tubes one end of each of which is closed, a holder provided with a series of sockets

therein into which the open ends of said tubes are inserted and retained, and a tubular coupling to one end of which said holder is secured and the bore of which is provided 5 with a transverse partition, and which is also provided near the end adjacent the said holder with a circumferential rib the periphery of which is flanged toward said holder, and a series of nozzles having one end 10 secured in said partition and the opposite end terminating adjacent the holder and adapted to discharge through openings therein into said tubes; the end edges of the coupling and the flange of said rib being recessed or 15 cut-away adjacent to and in the radial lines of the discharge ends of said nozzles.

10. An auto horn comprising a series of resonant tubes arranged around a common

center all of which are closed at one end, a coupling the bore of which has a transverse 20 partition dividing its bore into two portions, a series of nozzles the ends of which extend through and are secured in said partition, recesses in the end edge of said coupling adjacent the discharge ends of said nozzles, 25 and a holder having a series of sockets in which the open end portions of said tubes are inserted, and openings in the ends of said sockets adjacent said coupling.

In witness whereof I have hereunto set 30 my hand this 24th day of May 1912.

VICTOR E. TOLLEFSON.
